UNITED STATES PATENT OFFICE.

JOSEPH E. QUIGLEY, OF MINNEAPOLIS, MINNESOTA.

DRAIN DEVICE.

Application filed May 11, 1925. Serial No. 29,412.

This invention relates to a drain device, such as is placed in floors to drain off the water thereon and to which other drain pipes, such as the drain pipes from a sink, 5 drinking fountain, or refrigerator may be connected.

It is an object of this invention to provide such a drain device having a simple and efficient means thereon by which it can 10 be supported on a concrete slab in the floor or other means, and the cement or other flooring can be placed thereabout and in contact therewith.

It is a further object of the invention to 15 provide such a drain device having a central opening therein through which the liquid flows together with a dirt catching device about said opening, said device having a perforated cover at its top, said cover being imperforate at the portion aligned with 20 said opening.

It is still another object of the invention to 25 provide such a drain device comprising a casing having a discharge opening therein below its top and a dirt catching means about said opening and also having spaced portions at its sides to which drain pipes may be connected, said dirt catching portion being disposed below the opening in 30 such drain pipes.

It is also an object of the invention to 35 provide a drain device comprising a casing having a discharge opening therein below the top portion thereof and having a valve casing supported therein, which valve casing carries a float valve co-operating with a seat adjacent said discharge opening and said valve casing also having a discharge opening at its bottom with which said float 40 valve co-operates.

It is still another object of the invention to 45 provide a drain device comprising a casing and having a valve casing disposed therein below the top thereof, said valve casing having an inlet opening at its top and a discharge opening at its bottom, said first mentioned casing having a flange surrounding said valve casing having its top portion disposed a considerable distance 50 above the bottom of said valve casing, the wall of said first mentioned casing being spaced from said flange and having a discharge opening in its bottom, whereby the liquid flowing through said drain device 55 must pass out at the bottom of said valve casing, then pass up over the top of said

flange and then downward around said flange to the discharge opening in said first mentioned casing.

These and other objects and advantages 60 of the invention will be fully set forth in the following description made in accordance with the accompanying drawings, in which—

Fig. 1 is a view partly in front elevation 65 and partly in central vertical section of the device;

Fig. 2 is a horizontal section taken on line 2—2 of Fig. 1, as indicated by the 70 arrows; and

Fig. 3 is a horizontal section taken on the line 3—3 of Fig. 1, as indicated by the 75 arrows.

Referring to the drawings, the drain device is shown comprising a main casing 4. While this casing may be of various shapes, in the embodiment of the invention illustrated, the same is shown as substantially cylindrical having a rounded bottom which has a central projecting hub 4^a provided 80 with an interiorly threaded opening 4^b forming the discharge opening of the device and to which the drain pipe will be connected, which will lead to a sewer or other drain means. The casing 4 is adapted to be set 85 into a floor and to have its top flush with said floor or other surface to be drained, and said casing is provided a short distance from its top with an outwardly extending flange 4^c. The casing also has projecting 90 therefrom hubs 4^d and 4^e, illustrated as being disposed at opposite sides of the casing, which hubs are interiorly threaded to receive drain pipes, such as the drain pipe of a refrigerator or the drain pipe of a sink, 95 or drinking fountain. It will be noted that the flange 4^c is disposed substantially centrally of the hubs 4^d and 4^e in a vertical direction. The casing 4, as shown, is hollow 100 and has a narrow inwardly projecting flange 4^f at its top, which is recessed to form a shoulder for receiving a top cover plate 5 flanged to fit into said recess and to fit within the flange 4^f, the top of said cover being flush with the top of casing 4. The 105 cover 5 is provided with a multiplicity of perforations 5^a, as shown in Fig. 2, and while these perforations may be of any desired form and arrangement, in the embodiment of the invention illustrated, they are 110 shown as segments of annular slots radially arranged. The cover 5 is held in place by

suitable countersunk screws 6^c extending therethrough into the flange 4^f so that the cover may readily be removed by removal of said screws. It will be noted that the 5 central portion of cover plate 5 is imperforate and this imperforate portion is disposed over the central discharge opening adjacent the top of casing 4 to be later described. A short distance below the top of 10 casing 4, the same is provided with an inwardly extending flange 4^g forming a central opening and a valve casing 6 is disposed in this opening and extends downwardly quite a distance in casing 4, said valve 15 casing having a top flange 6^a resting on the flange 4^g. A gasket will be disposed between flanges 6^a and 4^g and flange 6^a is secured to the flange 4^g by cap screws 7, which screws, it will be noted, do not pass entirely 20 through the flange 4^g. The valve casing 6 has a central opening at its top and a member 8 is disposed in this opening, which member is formed as a shell or an open cylinder, and which has its bottom portion 25 flared to form a valve seat. The portion 8 has a flange 8^a adapted to form a gasket, and a dirt catching member 9 having a central opening, aligned with the opening through member 8, has a flange overlying 30 the flange 8^a and secured to the top of valve casing 6 by cap screws 10. The member 9 has a short upwardly extending flange or 35 central portion contracted toward its upper end and the top surface of member 9 is disposed a short distance below the bottom of the inside of the drain pipes 11 and 12, which are received in the hubs 4^d and 4^e, respectively, said pipes being indicated by dotted lines in Fig. 1. The valve casing 6 40 has a central opening in its bottom, the sides 6^b of which are formed on a bevel to constitute a valve seat, and a float ball valve 13 is provided in the valve casing adapted to co-operate with the seat 6^b and with the seat 45 formed at the lower portion of member 8. The casing 4 has a flange or wall 4^h extending about and spaced from the valve casing 6, the top of which is shown as disposed a short distance above the vertical center of 50 the valve casing 6. As shown in Figs. 1 and 3, the flange 4^h is connected to the wall of casing 4 by spaced radially extending ribs and it will be noted, as shown in Fig. 1, that the flange is spaced farther from casing 6 at its bottom portion than at its top portion. An annular chamber is thus formed 55 between flange 4^h and casing 6, which chamber extends beneath casing 6. It will also be noted that flange 4^h is spaced from the 60 wall of casing 4, so that an annular chamber 4ⁱ is formed between said flange and said wall with the bottom of which latter annular chamber, the opening 4^b communicates. The flange 4^h has a central threaded opening 65 at its bottom normally closed by a plug 14

threaded therein, which plug has an angular recess 14^a in its top adapted to receive a wrench for turning and removing the same. It will be noted that the opening in the top and bottom of valve casing 6 and opening 70 4^b are axially aligned with the opening in the bottom of flange 4^h.

In operation, the casing 4, as stated, will be placed in a floor or pavement with the top thereof preferably flush with the surface of said floor or pavement. It is a common practice to construct the floors of concrete and the casing 4 can be disposed in an opening formed in the concrete slab, which is usually a short distance below the top 80 surface of the floor, the casing being supported on the slab by the flange 4^h. The casing can thus be easily and quickly placed in position and trued up by means of said flange 4^h. It will only be necessary to cut 85 small recesses in the slab for the hubs or bosses 4^d and 4^e. After the casing is properly disposed in position, the floor can be finished with cement or other material, which will be placed in contact with the 90 portion of casing 4 above the flange 4^h. The drain water from the floor will run to the device and pass thereinto through the openings 5^a. It will be noted that the cover plate 5 is imperforate in the portion disposed 95 over the opening through member 9, so that the water cannot drop directly into said opening. The water passes into the annular trough formed about member 9 and must rise to a level above member 9 and run over the edge thereof into valve casing 6. Any heavy particles of dirt or foreign substance will remain in the annular trough and rest on the flange 4^g or the flange 6^a. As 100 stated, the top of member 9 will be below 105 the bottom of the openings in the pipes connected to hubs 4^d and 4^e, so that all liquid will drain out of said pipes and will not be backed up therein. The liquid flows in the 110 valve casing 6 and into the space between the valve casing and flange 4^h. After the liquid fills the chamber in side of flange 4^h, it will run over the top edge thereof into the chamber 4ⁱ and will then pass out into the drain pipe through opening 4^b. The 115 area of the annular chamber between flange 4^h and casing 6 is larger than the area of the openings through valve casing 6, so that ample space is provided for the discharge 120 of the liquid, and there will be no tendency for the liquid to fill up the drain and back up into valve casing 6. The liquid will be maintained in the drain at a level, as indicated in Fig. 1, horizontal with the top of flange 4^h. The ball valve 13 will normally 125 float at this level, so that the openings at the top and bottom of valve casing 6 normally are opened. If, for any reason, water should back up from the sewer or other place through the discharge drain pipe at the bot- 130

tom of the device, the level of liquid will be raised from the bottom of valve casing 6 and ball 13 will seat against the member 8 and close the opening at the top of the valve 5 casing, so that the liquid will be prevented from backing up through the drain through the cover plate 5 or into the pipes in hubs 4^a and 4^e. If the liquid should dry up in the drain, the ball valve 13 will rest on seat 10 6^b, so that the lower opening in the valve casing 6 will be closed and prevent the passage of gases back thru the drain. Normally, the liquid in the drain forms a seal preventing the passage of gases. The valve 15 casing 6 can readily be removed, when desired, by removing cover 5 and then removing screws 7. The valve casing 6 is of such diameter that it will readily pass through the opening in flange 4^g. If it is desired or 20 necessary, at times, to clean the drain pipe, cover plate 5 can be removed, as can also plug 14. A rod can then be projected through the drain into the drain pipe and reciprocated and moved therein. It may be 25 stated that the member 8 preferably will be made of rubber or similar material. The capacity of the drain is large, one standard size holding substantially three quarts of liquid as against one and one-half pints 30 held in drains of the prior art. It will be noted that there is an air space in the drain above the top of flange 4^g. This air space acts as a cushion and also acts to prevent siphoning of the liquid out of the drain casing. 35 The air in said chamber will break the vacuum, so that a siphon cannot be formed. In drains of the prior art, where the waste opening extends at the side and upwardly, it is a frequent occurrence that the liquid is 40 siphoned out of the drain. The lower opening in the casing is of ample size to take care of all liquid flowing into the casing and the passages about the valve casing 6 are of ample size to take care of any possible 45 discharge through the valve casing. If it is desired to test the water system in a building with the city pressure, it is unnecessary to close or seal the drain, as the ball valve 13 will be forced to its top seat and the drain will automatically seal and prevent the water running out through the top 50 thereof. If the drain pipes are not connected in the hubs 4^a and 4^e, they will, of course, be closed by suitable plugs.

55 From the above description, it is seen that the applicant has provided a simple and efficient drain device. The same is easily and inexpensively made and can conveniently be installed in place, and functions efficiently to carry off the water without any objectionable action. The parts, except the part 8, will be made of suitable metal. The top plate preferably being made of brass and nickel plated. The device is easily and inexpensively produced and the same has

been amply demonstrated by long service in actual practice and has been found to be very successful and efficient.

It will, of course, be understood that various changes may be made in the form, details, arrangement and proportions of the parts without departing from the scope of applicant's invention, which, generally stated, consists in a device capable of carrying out the objects above set forth in the novel parts and combinations of parts disclosed and defined in the appended claims.

What is claimed is:

1. A drain device comprising a receptacle having an open upper end, removable means disposed at said end for admitting liquid to said receptacle, means below the top of said receptacle extending inwardly from the wall thereof and having a central opening, a valve casing depending through said opening into said receptacle and removably supported on said means, and a member supported on said valve casing forming with said means a dirt catcher, said casing having a flange between its walls and said valve casing terminating below the top of said second mentioned means.

2. A drain device comprising a hollow casing having an opening at its top and a perforated plate disposed in said opening through which liquid passes to said casing, means at the sides of said casing adjacent its top adapted to receive inlet pipes, an inwardly extending flange in said casing immediately below said means having a central opening there through, a substantially cylindrical valve casing having solid walls with openings and valve seats at its top and bottom disposed in said central opening and having a flange overlying and secured to 105 said flange, said valve casing being removable through said central opening, a float valve in said valve casing adapted to co-operate with said seats, an annular member secured to the top of said valve casing having 110 a central opening alined with the openings therein and having an upwardly extending flange, said annular member and said inwardly extending flange forming an annular dirt catching chamber about the top 115 opening in said valve casing, said hollow casing having an opening in its lower end.

3. A drain device comprising a hollow casing, a perforated plate removably secured in the top thereof through which liquid passes to said casing, said casing having inlet means for liquid below said plate and having inwardly extending means below said inlet means having an opening there-through, a valve casing having a solid wall 120 removably secured in said opening, said valve casing having vertically alined openings at its top and bottom, a float valve adapted to co-operate with said openings, a liquid holding means in said casing between 125 130

- said valve casing and the wall of said casing, having an outlet below said inwardly extending means, said hollow casing having an outlet means at its bottom.
5. A drain device comprising a hollow casing, a valve casing disposed in said casings and having a top opening below top of said casing, said valve casing having an opening in its bottom, a dirt catching means 10 surrounding the opening in said valve casing, said first mentioned casing having a flange surrounding and spaced from the lower part of said valve casing and spaced from the walls of said first mentioned casing and forming a receptacle, the top of said flange being disposed a considerable distance above the bottom of said valve casing, said first mentioned casing having an opening in its bottom communicating with the 15 space between said flange and the wall of said first mentioned casing, said valve casing communicating through the opening in its bottom with the interior of said flange.
20. 5. The structure set forth in claim 4, said flange being spaced from said valve casing a greater distance adjacent the bottom of the latter than adjacent to the top of said flange.
25. 6. The structure set forth in claim 4, said opening in the top and bottom of said valve casing alining with the opening in the bottom of said first mentioned casing and said flange having a plug removable from its top therein alined with said openings whereby said plug can be removed and said last mentioned opening cleaned.
30. 7. A drain device comprising a hollow casing, a valve casing having a top opening disposed in said casing below the top thereof, said valve casing having an opening in its bottom, said first mentioned casing having a flange surrounding and spaced from said valve casing and spaced from the walls of said first mentioned casing, the top of said flange being disposed a considerable distance 35 above the bottom of said valve casing, said first mentioned casing having an opening in its bottom communicating with the space between said flange and the wall of said first mentioned casing, said valve casing having interior valve seats surrounding the openings in its top and bottom, a ball float valve adapted to co-operate with said seats, said ball normally being supported by liquid having a level at the top of said flange.
40. 8. The structure set forth in claim 1, said receptacle having a wall surrounding and spaced from said valve casing forming a container, said wall being spaced from the wall of said receptacle and terminating some 45 distance below said means, said receptacle having an outlet in its bottom.
9. A drain device comprising a hollow casing having an opening in its top, a valve casing having an opening in its top disposed in said casing, said valve casing having an opening in its bottom, said valve casing being removable through the top of said hollow casing, said hollow casing having a chamber closed at its bottom surrounding said valve casing, and an outer chamber surrounding said chamber and having an opening through the bottom of said first mentioned casing, said chambers at their upper ends communicating with an annular chamber in said first mentioned casing surrounding the upper portion of said valve casing.
10. A drain device comprising a hollow casing having an open upper end, a perforated plate removably seated in said upper end, a valve casing removably supported in 50 said hollow casing having openings at its upper and lower ends, a float valve in said valve casing adapted to close the opening in said upper and lower ends of the valve casing, said hollow casing having an opening in its bottom axially alined with the opening in said valve casing and said hollow casing having a wall forming a receptacle spaced from said valve casing and from the wall of said hollow casing, said wall having a plug 55 therein removable from the top and centrally and axially alined with the openings through said valve casing and hollow casing.
11. A drain device comprising an open top cylindrical hollow casing having a rounded bottom portion with an aperture therein, a perforated plate removably secured in the top of said casing, said casing having inlet means in its sides and an inwardly extending flange below said inlets having a central aperture, a valve casing depending through 60 said aperture and removably supported on said flange, said valve casing having an opening at its top and bottom, a member above said casing surrounding the opening in its top and disposed below said inlet means and forming with said flange a dirt catcher, said valve casing having valve seats at its top and bottom, a float valve co-operating with said seats to close said openings in the top and bottom of said valve casing, said first mentioned casing having a wall spaced from and surrounding said valve casing and also spaced from the wall of said first mentioned casing forming a container and terminating 65 some distance below said flange, and a plug removable from above secured in the bottom of said wall and in alinement with the opening in said valve casing and the aperture in the bottom of said first mentioned casing.
120. In testimony whereof I affix my signature.
JOSEPH E. QUIGLEY.
